UNITED STATES PATENT OFFICE.

WALTER L. CHENEY, OF MERIDEN, CONNECTICUT, ASSIGNOR OF ONE-HALF
TO BENJAMIN HOWARD WARREN, OF PITTSBURG, PENNSYLVANIA.

TRAVELER'S BRUSH.

SPECIFICATION forming part of Letters Patent No. 723,365, dated March 24, 1903.

Application filed October 6, 1902. Serial No. 126,065. (No model.)

To all whom it may concern:

Be it known that I, WALTER L. CHENEY, a citizen of the United States, residing at 26 Griswold street, Meriden, Connecticut, have 5 invented a new and useful Improvement in Travelers' Brushes, of which the following is a specification.

My invention relates to brushes to be used as blacking-daubers, for shaving, or for other 10 purposes, and provides convenient means of inclosing them when not in use, so as to prevent their soiling other articles packed with them.

In the accompanying drawings, Figures I 15 and II are sectional views of my device in its open and closed positions, respectively. Fig. III is a partial elevation showing a modification.

1 designates a wire or rod bent at 11, 12, 13, 20 and 14 and headed at 15. Swiveled at one end of the rod is a cap 2, having an internal thread 21. Transversely pivoted at the other end of the rod is a brush 3, the shell 31 of which is recessed at 32 to receive the head 15.

25 A case 4 of an internal diameter corresponding to the external diameter of the shell 31 is pivotally and longitudinally movable on the rod 1 by reason of the slot 41 in the tube. Both the open and the closed ends of the tube 30 4 are threaded at 42 and 43 to engage with the thread 21 of the cap 2.

Both the construction and operation of my device will be readily understood from an inspection of the drawings. It is obvious that 35 the rod 1 is bent at 14 after the cap 2 is *in situ*; also, that the case 4 and brush 3 are positioned before the head 15 is made on the other end of the rod, an aperture 44 having been made in the case 4 opposite the slot 41 for 40 this purpose. It will be seen that when the brush is open, as shown in Fig. I, the case 4 and rod 1 form a convenient handle therefor

and that the brush is held stiffly in position. By unscrewing the cap 2 from the case 4 both the case and the brush may be turned on the 45 rod 1, the case moved longitudinally thereon, and the cap screwed onto the open end of the case, as shown in Fig. II.

In Fig. III of the drawings I have shown the cap 2 and the case 4 as provided with 50 short screw-threads in the form of the well-known bayonet-joint. This is, of course, an old equivalent for the full threads shown in the earlier figures.

It is obvious that any sort of engagement 55 that serves to securely hold either end of the case in the cap is within the purview of my invention.

What I claim is—

1. An incased brush comprising a brush portion, a rod on which said portion is transversely pivoted, a case adapted to both pivotal and longitudinal motion on said rod and means for maintaining said brush portion and said case in both their operative and closed 60 65 positions.

2. An incased brush comprising a brush portion, a bent rod at one end of which said portion is transversely pivoted, a case adapted to both pivotal and longitudinal motion on 70 said rod and a cap at the other end of said rod and adapted to engage with either end of said case.

3. An incased brush comprising a brush portion, a bent rod at one end of which said portion is transversely pivoted, a case adapted to both pivotal and longitudinal motion on said rod and a cap pivotally attached at the other end of said rod and adapted to rotatably engage with either end of said case. 75

WALTER L. CHENEY.
